METHOD OF AND APPARATUS FOR SUPPORTING AND MANIPULATING LOOM HARNESS

Laurence R. Cox, Greer, S. C.

Application June 1, 1934, Serial No. 728,579

23 Claims. (Cl. 28—41)

My invention is apparatus for supporting and manipulating the harness of a loom during its repair or adjustment.

An important object of the invention is to provide apparatus of the above mentioned character, so constructed that the worn or damaged heddles may be removed and replaced without separating the warp from the remaining heddles.

A further object of the invention is to provide apparatus of the above mentioned character, which is so constructed that the work may be accomplished accurately and quickly.

A further object of the invention is to provide apparatus of the above mentioned character which will hold the harnesses and dropwires or dropwire rods, in a secure manner, whereby they may be inverted, when desired.

A further object of the invention is to provide apparatus of the above mentioned character which will permit of the entire separation and removal of the harness frame from the heddles.

Other objects and advantages of the invention will be apparent in the course of the following description.

25 In the accompanying drawings forming a part of this application and in which like numerals are employed to designate like parts throughout the same,

Figure 1 is a perspective view of apparatus embodying my invention,

Figure 2 is a plan view of the same,

Figure 1^a is a fragmentary plan view of the warp frame, showing an auxiliary end and associated elements.

35 Figure 3 is a transverse section taken on line 3—3 of Figure 2,

Figure 4 is a detailed section taken on line 4—4 of Figure 3,

Figure 5 is a side elevation of a harness,

40 Figure 6 is a transverse section taken on line 6—6 of Figure 5,

Figure 7 is a transverse section taken on line 7—7 of Figure 5,

Figure 8 is a transverse section through one of the heddle bars,

Figure 9 is an enlarged transverse section taken on line 9—9 of Figure 2,

Figure 10 is a plan view of a section of the cloth and warp threads, and,

50 Figures 11 to 19 inclusive are end elevations of the harness frames, showing the consecutive steps taken in the use of my apparatus in the repairing of the heddles and harness frames.

In the drawings, wherein for the purpose of illustration is shown a preferred embodiment of

my invention, the numeral 15 designates an outer stationary frame, which is preferably rectangular and embodies vertical ends 16, connected by horizontal side members 17, which are arranged near the bottoms of the ends, whereby the upper portions of the sides of the outer stationary frame are open. Extending or arranged at one side of the outer stationary frame is a horizontal shelf 18, upon which the harnesses rest, during the beginning of the operation, as will be described. 5

Disposed within the top of the outer stationary frame is a swinging or adjustable warp frame 19, which is preferably rectangular. This frame embodies ends 20, which are pivotally supported at their centers by bolts or pivots 21, which are attached to the upper portions of the ends 16. One end 20 is provided upon its outer side with openings 22, for receiving a lock pin 23, slidable within an opening formed in the end 15. When the warp frame 19 is in either of its horizontal positions, the pin 23 may be inserted into the corresponding opening 22 and will thereby lock the warp frame 19 in the horizontal position. The warp frame 19 further embodies a side 24, having a longitudinal slot 25, and a side 26, provided upon one edge thereof with a longitudinal groove 27, which is preferably slidably tapered in cross-section, decreasing in width downwardly. Adapted for insertion within the groove or recesses 27, is a clamping member 28, preferably having a 20 covering 29 of fabric. This clamping member is also slightly tapered in cross-section, decreasing in width inwardly. The clamping member 28 is adapted to be forced into the groove 27 and will wedge or clamp the warp within the groove 27, 35 as will be more fully explained. The side 26 and clamping element 28 therefore constitute the co-acting members of the clamp for binding the warp to the side of the warp frame.

The warp frame 19 is provided with harness 40 supporting devices, preferably arranged at a right angle thereto, and extending beyond the same, upon its opposite sides. Each harness supporting device embodies a rigid strap 30, formed of metal or the like, which is rigidly attached to the 45 end 20 by screws 31 or the like. The strap 30 is disposed at a right angle to the end 20 and extends beyond the same for substantial distances beyond its opposite sides. This strap is provided at one end with an opening 32, receiving the outer end of a horizontal rod 33, carrying clamping nuts 34, having screw-threaded engagement therewith. It is thus seen by manipulation of the nuts 34 the rod 33 may be longitudinally adjusted with relation to the strap 30 55

and locked thereto in a selected adjusted position. At its lower end, the strap 30 is provided with a longitudinal slot 34', receiving the end of a rod 35, having screw-threaded engagement with nuts 36. By manipulation of these nuts 36 the rod 35 may be shifted toward or from the rod 33 and also longitudinally adjusted with respect to the strap 30 and then clamped to the strap in the selected adjusted position. The rods 33 and 35 are arranged within the limits of the warp frame 20 and are horizontally disposed, and carry U-shaped brackets 37 upon their inner ends. Each rod extends through an opening in the base of the U-shaped bracket 37 and is clamped thereto by means of nuts 38. The U-shaped brackets have openings 39 formed in their sides to rotatably receive holding rods or elements 40, having laterally bent ends 41. Each holding element is rotatably mounted within the openings 39, and is held against longitudinal displacement by pins 42, inserted within the openings formed within the rod.

Disposed within the corners of the warp frame 19, next to the groove 27, are blocks 43, rigidly attached to the warp frame. These blocks have longitudinally extending grooves 44 formed in their upper surface for receiving dropwire rods 45 (Figs. 13 to 19). Each set of grooves is adapted to be covered by a latch-strap 46, having one end permanently pivotally attached to the side 26, as shown at 47, while the opposite end of the latch-strap has a transverse notch 48, to receive a bolt 49, attached to the block, and carrying a winged-nut 50. The latch-strap may therefore be clamped in the closed position, wherein it extends across the grooves 44.

The warp frame 19 may be formed in any desired length, so that the elements 40 will receive the harness frames. If desired, one end 20 and associated elements could be longitudinally adjustably mounted upon the sides 24 and 26. I also contemplate the provision of means whereby the warp frame 19 will handle unusually short harness frames. Such means comprises an additional end 20', Figure 1^a, which will be suitably mounted within the warp frame 19 inwardly of the adjacent end 20, and spaced from the remote end 20 a suitable distance, depending upon the length of the short harness frames. The same strap 30, and elements 33, 37 and 40 are employed. The same block 43 is mounted upon the end 20' having the same grooves and latch 46, but this latch is slightly shortened and pivoted directly upon the block 43.

In Figure 5, I have shown a loom harness designated as a whole by the numeral 51. This harness includes a harness frame embodying outer longitudinal slats 52, which are rigidly connected at their ends by iron end members or bars 53, attached thereto by any suitable means. These end members or bars are provided with slots 54, spaced inwardly from the slats 52 and arranged to receive heddle rods 55. These heddle rods are removable from the slots 54, and are normally held in place by hooks 56, preferably connected with the end bars 53, at 57, and having the ends adapted for insertion within openings 58 formed in the ends of the heddle bars. The heddle bars also pass through hooked studs 59 which are detachably connected with the slats 52. The heddle bars 55 carry the heddles 60, having outer eyes 61 which receive the heddle bars 55, and inner eyes 62 which receive the warp. In Figure 5, certain of the upper eyes 61 are shown as broken and certain of the lower eyes

61 as broken. Also the warp eyes 62 may become worn or broken. The numeral 63 designates a thin supplemental heddle bar which is threaded through the outer eyes 61 of the heddles, during the replacement operation, as will be more fully explained.

The operation of the apparatus is as follows:

The apparatus is not positioned in any particular relation to the loom and is ordinarily in a separate room from the loom. The warp beam 10 ordinarily runs empty of warp in about four weeks, and at this time it is customary to inspect the harness and make the necessary repairs, and it is seldom that repairs to the harness are made before the warp beam runs empty. Prior to my invention, when the warp beam ran empty, the harness was inspected or repaired, and the practice was to remove all of the warp from the heddle eyes, drop-eyes and reed. The harness was then removed from the loom and repaired, and when this was completed, the warp threads of a full warp beam were drawn by hand through the heddle eyes, drop-eyes and reed. This threading operation is very time consuming as it is done by hand. By the practice of my invention this threading in of the warp threads is entirely eliminated. In repairing the harness in accordance with the practice of my invention, when the warp beam has practically run empty, there still being a short length of warp threads wound 30 thereon, such as from one to three yards, the loom being at rest, the operator first removes the drop rods 45 carrying the drop wires from the loom and slides them along the warp thread until they are brought into contact with the harness 35 frames, Figure 11, and he then ties the ends of the drop rods to the harness frame. He then slips the warp beam out of gear and cuts the cloth 64, Figure 10, along the lines 65, leaving a narrow strip of the cloth permanently attached 40 to the warp threads 66. He next removes the reed 67 from the reed cap. He next turns the warp beam by hand for winding up the warp thread thereon which will slide through the heddle eyes and drop-eyes and the cut cloth 64 will 45 bring the reed 67 in contact with the side of the harness frame or heddles, Figure 11. It is thus seen that the drop rods, harness frames and reed are closely assembled to produce a unit, Figure 11, which is known as a pattern unit and this pattern unit is next removed from the loom. To accomplish this, the short length of warp thread 66 is unwound from the warp beam and the end of these warp threads are loosely tied, as shown at 68. The pattern unit is now bodily removed from 55 the loom and carried to my apparatus adjacent to the side 24 of the warp frame 19 and this unit is bodily lifted over the side 24 and placed upon the shelf 18, in a more or less vertical position, on edge, Figure 12. The warp frame 19 is now locked 60 in the horizontal position and the reed 67 is passed through the slot 25 until it is arranged adjacent to and outwardly of the side 24, Figure 13. The warp threads are now passed over the side 26 and smoothed out and drawn somewhat tight 65 and then the clamp element 28 is forced into the groove 27 which further tightens the warp threads and holds them against slipping, Figure 14. The clamp element is tied to the side 26 by a cord or the like and the warp threads are securely 70 clamped to the side 26 of the warp frame. The drop rods 45, carrying the drop wires, not shown, are now untied from the harness frames and slid forwardly upon the warp threads and are introduced into the grooves 44 and are held therein by 75

the elements 46, Figure 15. As stated, the harness frames are now supported on edge in a more or less vertical position and the upper heddle rods 55 are removed from the end bars 53 and are thus separated from the harness frame, Figure 16. These upper heddle rods 55 still remain within the eyes 61 of the heddles and are supported thereby and the upper portions of the heddles may be shifted forwardly along the warp threads toward the drop rods 45. When the removed upper heddle rods 55 are in this freed position, the supplemental heddle rod or bar 63 is now threaded through the upper eyes 61 of the heddles 60, Figure 8, but is not threaded through the heddle eyes which are worn or need replacement. The upper heddle rod 55 is now bodily removed from all of the heddle eyes 61. The perfect heddle eyes remain on the supplemental heddle bar 63, while the imperfect heddle eyes are not mounted thereon. The lower heddle eyes 61 must also be inspected when this change is made so that any heddle 60 having worn or damaged upper or lower heddle eyes or worn or damaged eyes 62, will thus be omitted from the supplemental heddle bar 63. The warp threads connected with the damaged heddles 60 are now broken and new heddles substituted for the damaged or worn heddles and the broken warp threads passed through the eyes 62 of the new heddles and tied. The upper heddle rod or bar 55 is again threaded through all of the upper eyes 61 of the old retained heddles and the new heddles, and after this the supplemental heddle rod or bar 63 is withdrawn, leaving all eyes 61 upon the upper heddle bar 55. The top of each harness is treated in a similar manner for replacing worn or damaged heddles. During this operation the harness frames have remained supported on edge on the shelf 18. The operator next places two steel rods 69, Figure 17, upon the horizontally arranged warp frame 19 and these rods rest upon the side 26 and the reed 67 and also pass through the harness frames 51. The harness frames are now removed from the shelf 18 and their lower portions may be slid to the outside of the stationary frame 15, the lower sides 52 of the harness frames projecting exteriorly of the frame 15 at the side thereof while the upper slats 52 are supported by the steel rods, Figure 17. The operator now removes the hooks 56 and hook studs 59, and replaces them, if necessary. After the replacement is made the harness frames may again be rested upon the shelf 18 and are then mounted upon the holding rods 40, Figure 18, the extensions 41 being manipulated so that this may be accomplished and then directed outwardly to retain the harness frames thereon. The pin 23 is now removed and the warp frame 24 is turned for 180° to invert the same, Figure 19, and is again locked in the horizontal position. The harness frames are now removed from the holding rods 40 and supported on edge upon the tray 18, and the same cycle of operation is again performed to remove the worn heddles from the then upper bar 55 and substitute new heddles, and also for repairing the then lower slats of the harness frames. After the heddle rods or bars 55 at the top position, have thus been assembled in the harness frames, these harness frames are again returned to position upon the hold rods 40 and are held thereon. The warp frame 19 is again inverted and the harness frames are again removed from the rods 40 and supported on edge upon the shelf 18, and the then upper heddle rods or bars 55 are inserted within the openings 54 of the ends 53. The drop rods 45 are now removed from the grooves 44 and are again shifted into contact with the heddle frames and are tied thereto. The clamp element 28 is now removed from the groove 27 and the warp threads 66 freed. These warp threads may now be pulled toward the side 24 so that the reed 67 may be shifted a slight distance from the side 24 and passed inwardly through the slot 25 and the warp threads may again be pulled toward the side 23 so that the reed will be drawn into contact with the harness frames. Their parts will then assume the position shown in Figure 12. It is thus seen that the drop rods, harness, and reed constituting the pattern unit are separated from the warp frame and may now be lifted out of the same. This unit is now taken to a machine which will tie the free ends of the warp threads 66 with the warp threads of a full warp beam, and the unit is next carried to the loom with this full warp beam and the several parts of the pattern unit are again assembled in the loom and the cloth strip 64 is stitched to the end of the cloth in the loom. The loom is now ready to be operated in the usual manner.

Having thus described my invention what I claim is:

1. In apparatus for use in repairing the warp thread carrying harness of a loom, a relatively stationary outer support having a part serving as a supporting element for the harness, a warp frame pivotally mounted upon the relatively stationary support so that it may be turned and inverted with relation thereto, said warp frame having one side provided with a longitudinal slot for the passage of the reed of the loom, clamping means associated with the opposite side of the warp frame for engaging with the warp thread, and means mounted upon the warp frame for movement therewith and adapted to removably receive the harness.
2. In apparatus for use in repairing the warp thread carrying harness of a loom, a relatively stationary support including a tray for supporting the harness, a warp frame movably mounted upon the support so that it may be inverted with relation thereto, one side of the warp frame being adapted for engagement with the reed, clamping means associated with the opposite side of the warp frame for engaging the warp thread, and means mounted upon the warp frame for movement therewith and adapted to removably receive and hold the harness.
3. In apparatus for use in repairing the warp thread carrying harness of a loom, a relatively stationary support, a warp frame movably mounted upon the support so that it may be inverted with relation thereto, means whereby the warp thread may be connected with one side of the warp frame, means whereby the warp thread may be connected with the opposite side of the warp frame, and means mounted upon the warp frame for movement therewith and adapted to removably receive and hold the harness.
4. In apparatus for use in connection with the drop rods, harness, and reed of a loom for repairing the harness, a support, a warp frame pivotally mounted upon the support to turn upon its longitudinal axis with relation thereto so that it may be inverted and having means for holding the drop rods, releasable means for locking the warp frame in substantially horizontal positions, means whereby the warp thread adjacent to the reed may be secured to one side of the warp

- frame, means whereby the warp thread may be secured to the other side of the warp frame, and means mounted upon the warp frame to move therewith and adapted to hold the harness at generally a right angle to the plane of the warp frame.
5. In apparatus for use in repairing the harness of a loom, a supporting frame, a warp frame extending longitudinally of the supporting frame and pivotally connected therewith, a warp thread carrying harness supporting device mounted upon the warp frame between the sides of the same and extending transversely of the ends of the warp frame, said warp frame being provided with means whereby the warp threads may be attached to its opposite sides, and a support arranged near the supporting frame and lower than the pivotal connections between the warp frame and the supporting frame and serving to support the harness when separated from the harness supporting device.
10. In apparatus for use in repairing the warp thread carrying harness of a loom, a supporting frame, a warp frame extending longitudinally of the supporting frame and pivotally connected therewith and provided near one side with means for holding drop rods, a harness supporting device mounted upon the warp frame between its sides, and a harness supporting element attached to the supporting frame near one side thereof.
15. In apparatus for use in repairing the warp thread carrying harness of a loom, a supporting frame, a warp frame pivotally connected therewith so that it may be inverted, means to lock the warp frame in a generally horizontal position, a harness supporting device mounted upon the warp frame, a supporting element arranged near one side of the supporting frame, and rods adapted to be placed upon the warp frame for supporting the upper side of the harness so that its lower side may be shifted into engagement with the supporting element.
20. In apparatus for use in repairing the warp thread carrying harness of a loom, a supporting frame embodying a harness supporting element disposed adjacent to one side thereof, a warp frame pivotally mounted upon the supporting frame to be inverted with relation thereto, members attached to the ends of the warp frame and extending laterally beyond the opposite sides of the same, devices carried by the opposite ends of each member for engaging with the harness, and means for securing warp thread to the sides of the warp frame.
25. In apparatus for use in repairing the warp thread carrying harness of a loom, a warp frame having one side provided with a longitudinal slot through which the reed may be bodily passed in an outwardly direction so that it may engage such side while disposed outwardly thereof, a clamp member for coaction with the opposite side of the frame for engaging with the warp threads, and means mounted upon the warp frame to support the harness.
30. 10. The combination with a warp thread carrying harness frame provided in its ends with openings, heddle rods to be held within the openings, heddles having eyes to be strung upon the heddle rods, and a supplemental heddle bar to be moved into the heddle eyes in the presence of the heddle rod therein, both bars being inserted in selected eyes so that such selected eyes are transferred to the supplemental bar upon the removal of the original bar, and adjustable means for supporting the

harness frame so that the sets of eyes may be shifted to a work position.

11. In apparatus for use in repairing the warp thread carrying harness of a loom, a supporting structure, a support, means for supporting the support from the supporting structure so that the support may be turned and inverted, devices carried by the support for holding the harness, and means for holding the warp threads so that they are retained within the heddle eyes.

12. In apparatus for use in repairing the warp thread carrying harness of a loom, a supporting structure, a support, means for supporting the support from the supporting structure so that the support may be turned and inverted, means carried by the support for holding the harness, and means for attaching the warp threads to the support so that they are retained within the heddle eyes.

13. In apparatus for use in repairing the warp thread carrying harness of a loom, a shiftable support, means carried by the support for holding the harness, each side of the harness being brought to a work repair position by the shifting of the support, and means for attaching the warp threads to the support so that they are retained within the heddle eyes.

14. In apparatus for use in repairing the warp thread carrying harness of a loom, a shiftable support, means carried by the support for holding the harness, each side of the harness being brought to a work repair position by the shifting of the support, and means carried by the support for holding the warp threads in their normal orderly arrangement and retaining them in the heddle eyes.

15. In apparatus for use in repairing the warp thread carrying harness of a loom, a shiftable frame having sides, means mounted upon the frame between the sides for holding the harness, each side of the harness being brought to a work repair position by the shifting of the support, and means for securing the warp threads to the sides of the frame for holding them in substantially their normal orderly arrangement and retaining them in the heddle eyes.

16. In apparatus for use in repairing the warp thread carrying harness of a loom, a shiftable frame having sides, means mounted upon the frame between its sides for holding the harness, each side of the harness being brought to a work repair position by the shifting of the frame, and means carried by the frame for holding the warp threads and retaining them in the heddle eyes.

17. In apparatus for use in repairing the warp thread carrying harness of a loom, a frame having sides and means for holding drop rods, means mounted upon the frame between the sides for holding the harness, and means for securing the warp threads to the sides of the frame and retaining the same within the heddle eyes.

18. In apparatus for use in repairing the warp thread carrying harness of a loom, a frame having sides, means carried by the frame between the sides for holding the harness in a position within the frame and between the sides of the frame, and means for securing warp threads to the sides of said frame and retaining the same within the heddle eyes.

19. In apparatus for use in repairing the warp thread carrying harness of a loom, a pivoted support, means carried by the pivoted support for holding the harness so that each side of the harness may be moved to a work repair position, and a stationary supporting element for the harness

when it is separated from the harness holding means.

20. In apparatus for use in repairing the warp thread carrying harness of a loom, a pivoted support, means carried by the pivoted support for holding the harness so that each side of the harness may be moved to a work repair position, supporting means to be passed through the harness when it is separated from the harness holding means, and a stationary supporting element disposed at a lower elevation than the supporting means for supporting the harness when separated from the holding means.

21. The method of repairing the harness of a loom by substituting new heddles for worn heddles, comprising removing the drop rods, harness, reed and warp threads as a unit from the loom, supporting the drop rods, harness, reed and warp threads, connecting only the eyes of the unworn heddles, removing the heddle bar from the eyes of all of the heddles so that the eyes of the unworn and worn heddles are separated, placing new heddles in positions for substitution for the worn heddles, connecting the eyes of the unworn heddles and the new heddles by inserting the heddle bar through such eyes only, disconnecting the connected eyes of the unworn heddles, shifting the harness to bring the other side thereof to the work repair position, and treating the heddle eyes at this other side in the same manner.

22. The method of repairing the harness of a loom, comprising supporting the harness, holding the warp threads upon opposite sides of the harness to retain them within the heddle eyes, treating the heddle eyes in each set by connecting only the eyes of the unworn heddles, removing the heddle bar from the eyes of all of the heddles so that the eyes of the unworn and worn heddles are separated, placing new heddles in position for substitution for the worn heddles, connecting the eyes of the unworn heddles and the new heddles by inserting the heddle bar through such eyes only, and then disconnecting the eyes of the unworn heddles.

23. The method of repairing the harness of a loom, comprising supporting the harness, retaining the warp threads within the eyes of the heddles, treating the heddle eyes in each set by connecting only the eyes of the unworn heddles, removing the heddle bar from the eyes of all of the heddles so that the eyes of the unworn and worn heddles are separated, placing new heddles in position for substitution for the worn heddles, connecting the eyes of the unworn heddles and the new heddles by inserting the heddle bar through such eyes only, and then disconnecting the previously connected eyes of the unworn heddles.

LAURENCE R. COX. 30
